(57) **CLAIM**

The ornamental design for a hummingbird feeder, as shown and described.

DESCRIPTION

FIG. 1 is a top perspective view of a hummingbird feeder, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a top perspective view showing the hummingbird feeder, in configuration of use.

All the broken lines in the drawings depict portions of the hummingbird feeder that form no part of the claimed design.

1 Claim, 8 Drawing Sheets(56)
